DUAL ROTATION COAXIAL PROPELLER
MECHANISMEarl M. Frankland, Manchester, Conn., assignor
to United Aircraft Corporation, East Hartford,
Conn., a corporation of Delaware

Application May 18, 1950, Serial No. 162,728

9 Claims. (Cl. 170—135.27)

1
This invention relates to dual rotation propellers and more specifically to improvements for interconnecting the several units of such propellers.

It is an object of this invention to provide an improved inter-propeller mechanism and housing for dual rotation propellers.

Another object of this invention is to provide an interpropeller housing for dual rotation propellers which housing is normally stationary relative to the rotating propeller units whereby the sealing means interposed between the propeller units and the housing is subjected to relative rotational speeds which are substantially equivalent to the rotational velocity of one of the propeller units.

Another object of this invention is to provide a drive for the integral pumps of dual rotation propellers whereby the normally stationary interpropeller housing is operatively connected to the pumps so that during propeller rotation the pumps will be driven at a rotational speed equivalent to the speed of any one propeller component.

A further object of this invention is to provide means for transmitting power from one rotating unit to another of a dual rotation propeller whereby the cooperating electrical connectors are subjected to relative speeds not in excess of that of any one propeller component.

A still further object of this invention is to provide a synchronizing mechanism for the blade settings of the several rotating units of a dual rotation propeller which comprises gear trains interconnecting the units and spanning the axial space therebetween.

Another object of this invention is to provide a stationary housing for a synchronizing mechanism of the type described wherein the housing carries some of the gear elements and provides a fluid tight chamber surrounding the gear mechanism; this fluid chamber thus forming an axial extension of, and communicating with, a lubricating chamber carried by the outboard or forward propeller unit.

These and other objects of this invention will become readily apparent from the following detail description of the accompanying drawings in which:

Fig. 1 is an illustration of a dual rotation propeller having an interpropeller housing construction according to this invention.

Fig. 2 is a cross-sectional view of Fig. 1 with portions of the section taken along arbitrary planes to conveniently illustrate the majority of the operating units.

2
Fig. 3 is a schematic showing of the Fig. 2 illustration.

Fig. 4 is a perspective and schematic showing of the inter-propeller connecting mechanism.

Fig. 5 is a detail cross-sectional view of the intershaft sealing mechanism.

Referring to Fig. 1, a dual rotation propeller is shown having an inboard unit 20 and an outboard unit 22, respectively, each of which include the hubs 24 and 26, respectively, and a plurality of blades 28 and 30 mounted for pitch changing movements relative to the hubs. The propeller units are driven by a power plant 40 in opposite directions at a fixed ratio or equal speeds by a well-known means omitted herein for convenience. The propeller units 20 and 22 include an interconnecting mechanism therebetween including a housing 44 which normally remains stationary during propeller rotation whereby the sealing mechanism 46 interposed between the outboard propeller unit 22 and the housing 44 and the sealing mechanism 48 interposed between the inboard propeller unit 20 and the housing 44 are subjected to only one-half the relative velocity between the two propeller units. In other words, the sealing mechanisms 46 and 48 are subjected to a relative rotational velocity which is substantially equivalent to that of only one of the propeller units.

The pitch of the propeller blades 28 and 30 may be varied by means of fluid operated motors such as for example illustrated and described in patent application Serial No. 154,857, filed April 8, 1950, by Arthur N. Allen, Jr. and now Patent No. 2,667,229.

In order to properly synchronize and coordinate the pitch changing movements of the blades of the several propeller units, it is desirable to provide a simple yet efficient interconnecting mechanism between these propeller units. To this end (Fig. 2) the inboard propeller hub 24 is driven by an outer shaft 50 while the outboard propeller hub 26 is driven by an inner concentric shaft 52. The inboard hub 24 includes a blade interconnecting gear 56 which synchronizes the pitch changing movements of all of the blades mounted within the hub 24. The synchronizing gear 56 is connected by means of a gear train (to be described in detail hereinafter) to the distributor valve 60 located within the outboard hub 26 so that pitch of the blades 30 on the outboard hub 26 will be varied in response to the pitch changing movements of the blades 28 of the inboard hub 24. Thus, the blade synchronizing gear 56 of the inboard hub 24 includes a forward extending sleeve 64 which has a

splined connection with a ring gear 66 which in turn meshes with a gear 68 journalled within the hub 24. The gear 68 drives another gear 70 by means of a common shaft 72. The gear 70 meshes with a ring gear 74 which is carried by an aft extending portion of a freely rotatable sleeve 76 forming a part of the interpropeller connecting mechanism contained within the aforementioned housing 44. The sleeve 76 has a forward extending portion 78 which carries a ring gear 80. The ring gear 80 is connected to another ring gear 82 of similar diameter by means of a plurality of reversing gears, described hereinafter in connection with Figs. 3 and 4, so that when the gear 80 is driven in one direction, the gear 82 will move in an opposite direction. The gear 82 is carried by a freely rotatable sleeve 84 which in turn carries a cam track 86 located within the aft portion of the outboard hub 26. A cam follower 88 cooperates with the cam track 86 in such a manner that rotation of the sleeve 84 will cause the cam follower 88 to rock about its pivot 90 so as to reciprocably move the spool 92 of the distributor valve 60. The distributor valve 60 in turn will direct high pressure fluid to the propeller pitch changing motors of the outboard hub unit 26 and change the pitch of said blades as described in detail in the above-referenced patent application.

The high pressure fluid may be provided by a pump 100 which takes in fluid from a pressurized sump 102 and directs it to the distributor valve 60. The pump 100 is carried by the hub 26 and is normally driven in response to propeller rotation by a gear 104 which is interconnected to a gear 106 fixed to the normally stationary interpropeller housing 44. Thus the housing 44 serves as a pump drive during propeller rotation in addition to having utility for other purposes described herein. By connecting the pump gear 104 to the housing 44 the pump 100 can be driven at a speed substantially equal to the rotational speed of one of the propeller components.

During the pitch changing movements of the blades 30 of the outboard hub 26, the blade synchronizing gear 110 which interconnects each of these blades will be rotated an equivalent amount. The blade interconnecting gear 110 has a splined connection 112 to a blade follow-up gear 114 which in turn is capable of rotating the gears 116 and 118 carried by a common shaft 120. An adjusting mechanism 124 is provided for adjusting the position of the shaft 120 and the gears carried thereby relative to the blade follow-up gear 114. The blade follow-up mechanism and interconnecting gearing just described is connected by means of a second gear train to the hub 24 of the inboard propeller unit 20 in a manner now to be described. To this end, the gear 118 on the shaft 120 engages a gear 130 freely rotatable on a spindle 132 journalled within the hub 26. The gear 130 also engages a gear portion 134 carried at one end of a freely rotatable sleeve 136 which carries at its other end a gear 138. The gear 138 is interconnected in turn to a gear 140 of similar diameter by means of a reversing gear mechanism also to be described hereinafter. The gear 140 is carried by a freely rotatable sleeve 142 which is splined at 144 to a sleeve 146 fixed to the inboard hub 24 by means of bolts 148.

The reversing gears mentioned hereinbefore are journalled within the interpropeller housing 44 in such a manner that during the equal and opposite rotation of the propeller hubs 26 and 24 the entire housing 44 normally remains sta-

tionary. The housing 44 includes a substantially annular outer wall portion 150 and an integral sleeve 152 which is radially spaced inwardly from the wall portion 150. The sleeve 152 is fixed to an outer ball bearing race 154 which in cooperation with the balls 156 and an inner race 158 serves to support the entire housing 44 on the rotating inner concentric drive shaft 52.

The forward extremity of the wall 150 carries a rubber U-shaped seal 160 held in position by a garter type spring 162. The upstanding portions of the seal 160 cooperate respectively with a pair of depending flanges 164 and 166 which are fixed by means of bolts 168 to a rear closure member 170 of the hub 26.

The closure member 170 forms a chamber 172 which is normally at atmospheric pressure and accumulates lubricating oil which is supplied to the gears located therein. Although not illustrated herein, a scavenging pump normally takes fluid from the chamber 172 and exhausts it at a certain pressure into the pressurized sump 102 from whence it is taken by the high pressure pump 100 and fed to the distributor valve 60. The pumping system just described is shown in more detail in the above-mentioned co-pending patent application. The aft axial extremity of the wall 150 carries a depending flange 180 which cooperates with a rubber seal 182 fixed by a garter type spring 184 to a sleeve 186 which in turn is fixed to, and rotatable with, the inboard hub 24. It is thus apparent that since the housing 44 is normally stationary relative to each of the propeller units, the seals 160 and 182 adjacent the fore and aft extremities respectively of the housing 44 will be subjected normally to no more than the rotational velocity of one of the propeller units. It is further apparent then that the housing 44 spans the axial space between each of the propeller hubs 24 and 26 so as to form a fluid tight closure member for the gear mechanism which interconnects the operating units in each of the two propeller components.

As further viewed in Fig. 2, it can be seen that the outer concentric drive shaft 50 terminates at 190 adjacent the inboard propeller hub and has a retaining nut 192 threaded thereto for fixing the hub 24 thereto. Therefore, it becomes necessary to provide a sealing mechanism, generally indicated at 196, between the drive shafts 50 and 52 so that lubricating fluid within the interpropeller housing 44 will not drain back toward the engine or power plant 40. The sealing mechanism 196 is more clearly illustrated in Fig. 5. As viewed herein, the concentric shaft 52 extends forward of the end 190 of the outer drive shaft 50 and the sealing mechanism 196 is interposed between the forward (outboard) extending portion 193 of the inner shaft 52 and the inner periphery of the retaining nut 192. The sealing mechanism 196 comprises a collar 200 which is fixed for rotation with the inner shaft 52, a carbon seal ring 202 and a shoe 204 which is rotatable with the outer shaft 50 and engages the inner periphery of the retaining nut 192. The shoe 204 is biased against the carbon ring 202 by means of a spring 206 which is partly enclosed in a hollow plug 208 which engages a tapered wall portion 210 of the retaining nut 192. It is then apparent that the sealing mechanism 196 just described and the seals 160 and 182 adjacent the extremities of the interpropeller housing 44 serve to completely enclose the interpropeller gear mechanism and form a fluid tight chamber which is in communication with the

chamber 172 in the aft end of the outboard hub 26.

Referring again to Fig. 2, lubricating means is provided for the gears housed within the housing 44 by means of a sleeve 230 which includes a plurality of axial slots 232 spaced apart on its inner periphery. The slots 232 communicate with an annular groove 234 which receives lubricating fluid under pressure from a source within the hub 26 via passages omitted for convenience. Each of the grooves 232 communicates with at least one port, as for example at 236, to provide lubricating fluid to the bearings and rotating gears adjacent thereto. It will be noted that the sleeve 230 extends aft of the hub 26 so that the rear or inboard extending portion 240 thereof is radially spaced from the inner shaft 52 thus forming an annular chamber 241. Each of the slots 232 in the sleeve 230 extend into the chamber 241 so that lubricating fluid can flow in an inboard direction, as indicated by the arrows, in order to lubricate the main roller bearings 242 which support the forward portion of the hub 24 on the inner drive shaft 52. Any fluid moving past these roller bearings 242 will, of course, be prevented from flowing inboard between the drive shafts 50 and 52 by the sealing mechanism 196 previously described.

Inasmuch as the interpropeller housing 44 is normally stationary relative to the propeller units and the gears therein are normally rotating, any excess oil which thrown outwardly by the gears or otherwise accumulates in the casing will tend to drain in a forward direction into the chamber 172 in the aft end of the outboard propeller unit.

In order to provide a transfer of electrical power from the inboard hub 24 to the outboard hub 26 the housing 44 is also utilized to carry a brush assembly 250 which includes a plurality of conducting brushes 251, 252 biased apart by a spring 253. The brushes 251 engage annular slip rings 254 on the outboard side of the inboard hub 24 while the brushes 252 engage annular slip rings 255 on the inboard end of the outboard hub 26. The springs 253 may serve to conduct current between brushes 251 and 252. The slip rings 255 may in turn be operatively connected to electrically operated elements of the outboard propeller component particularly electrical deicing equipment for the blades 30 thereof (omitted for convenience). It will be noted that the relative speeds between the brushes 251 and the slip rings 254, or between the brushes 252 and 255 will be no more than the speed of any one of the respective hubs. To this end wear and malfunction were reduced considerably.

The gear trains which provide the interconnection between the propeller units and which are substantially housed within the interpropeller housing 44 are more clearly illustrated in Figs. 3 and 4. As shown herein, the blades 28 are connected by means of the blade interconnecting gear 56 and the gears 68, 70 and 74 to the gear 80. The gear 80 meshes with the gear 280 mounted on a shaft 282 which in turn is freely rotatable in bearings 284 carried by the wall 150 of the interpropeller housing 44. The gear 280 in turn meshes with another gear 286 which is fixed to a shaft 288 mounted in bearings 290. The shaft 288 also has fixed thereto a gear 292 which engages the gear 82. The gear 82 as previously described is fixed to, and integral with, a cam track 86 which guides the cam follower 88 so as to pivot the latter about its pivot 90 and thereby actuate the distributor valve 60 during pitch changing.

movement of the blades on the inboard component. When no pitch change is taking place, however, the blade interconnecting gear 56 is rotating at the same speed as the inboard hub 24 while the distributor valve and its cam following mechanism is rotating in the opposite direction along with the hub 26 of the outboard component. Hence, by means of the gear train 80, 280, 286, 292 and 82 the cam track 86 rotates at the same speed as the cam follower 88 and the valve 60 so that no pitch changing movements are effected in the outboard component. However, in the event that the blades 28 on the inboard component are actuated for pitch changing movement in either direction, the result will be that the blade interconnecting gear 56 carried by the inboard hub 24 will momentarily move faster or slower than the speed of the hub 24 so that via the gear train just mentioned the cam track 86 will slow up or speed up in a reversing sense with respect to the cam follower 88 and the distributor valve 60 so that relative movement will take place between the cam track 86 and the cam follower 88 and cause the follower 88 to pivot about the point 90 to actuate the distributor valve 60.

The distributor valve 60 will, of course, cause the blades on the outboard component to vary their pitch so that the blade interconnecting gear 110 on the outboard component will rotate relative to its respective hub and cause a faster or slower movement relative to the outboard hub 26 through the follow-up gear 116, gears 118, 130, 134 and the gear 138. As previously mentioned, the gear 138 is connected through the elements of its reversing train to the gear 140 which is fixed for equal and opposite rotation to the inboard hub 24. With this fixed relation then, the reversing gear elements of the follow-up train which are journaled with the housing 44 will cause the housing to rotate slightly and to effect the motion of the reversing gears 280, 286, 292 which are also housed therein so that cam track 86 will return to a position whereby the cam follower 88 and the distributor valve 60 are no longer calling for a pitch change.

The above-mentioned reversing gear elements of the follow-up gear train which are connected to the gears 138 and 140 comprise a gear 300 meshing with the gear 138 and carried by a shaft 302 journaled in bearings 304 and 305 carried by the walls 150 of the housing 44. The gear 300 meshes with a gear 310 which is fixed to a shaft 312 journaled in bearings 314 and 316 also carried by the wall 150. The shaft 312 also has fixed thereto a gear 320 which meshes with a ring gear 140 carried by the sleeve 142 and is splined at 144 to the hub 24 of the inboard propeller component.

Summarizing, then, the general operation of the interpropeller connected gear mechanism (referring to Figs. 3 and 4), it will be apparent that since the outboard hub 26 and the inboard hub 24 are driven at equal and opposite speeds, the blade interconnecting gear 110 carried by the outboard hub and associated follow-up mechanism 116, 118 and 130 will be stationary relative to the outboard hub 26 and will rotate the gear 134 at the speed of the outboard hub. The gear 134, in turn, will cause the gear 138 to rotate at an equal and opposite speed relative to the gear 140 which is fixed to, and rotates with, the inboard hub 24. Hence, the reversing gears 300, 310 and 320 which are journaled in the housing 44 will maintain the housing normally fixed except when a pitch change is taking place in the outboard propeller component. With the housing

44 held stationary, should a pitch change take place in the inboard component, a relative increase or decrease in speed is transmitted from the blade interconnecting gear 56 of the inboard hub 24 through the gears 68, 70, 74, 80 and through the reversing gears 280, 286, 292 and finally to the gear 82 and the cam track 86. Thus, the distributor valve 60 on the outboard component will be actuated in response to pitch changing movement of the blades of the inboard component while the housing 44 remains stationary. Then as previously described, as soon as a pitch change is produced in the outboard component the follow-up mechanism carried by said component will cause the gear 138 via the train 116, 118, 130, 134 to speed up or slow down relative to the outboard component rotational velocity so that the normally equal and opposite relative rotational speed between the gears 138 and 140 is momentarily disrupted so that the reversing gears 300, 310 and 320 will translate this unequal velocity to the housing 44 by means of their shafts 302 and 312. The housing 44 will then rotate a slight amount in either direction to vary the relationship between the gears 80 and 82 and their reversing gears 280, 286 and 292 in the pitch change gear train. This variation of relationship will then tend to return the cam track 86, follower 88 and the distributor valve 60 to a valve neutral position so as to stop the pitch changing movements of the outboard component at a desirable setting.

It is therefore apparent that as a result of this invention a positive and compact synchronizing mechanism has been provided for maintaining the proper pitch change relationship between the blades of the several components of a dual rotation propeller.

Further, as a result of this invention means have been provided for enclosing this synchronizing mechanism in an efficient manner whereby a fluid tight lubricant chamber is provided. The provision of an enclosure of the type described, which enclosure normally remains stationary relative to the oppositely rotating propeller components, greatly decreases leakage problems due to the fact that the seals between the stationary housing and the hubs of the rotating components are subjected to rotational speeds not exceeding that of any one component. With reduced wear, leakage is reduced. The same holds true in regard to the relative velocities of the brushes and slip rings which transmit power between the hubs. The importance of this relative speed reduction and wear reduction can be seen by the fact that it is generally known that wear increases somewhere in the order of the cube of the speed. Hence where the speed between relative parts does not exceed that of any one unit the wear is approximately one-eighth that existing where the relative speed is the sum of the units.

Although only one embodiment of this invention has been illustrated and described herein, it will be apparent that various changes and modifications will be made in the construction and arrangement of the various parts without departing from the scope of this novel concept.

What it is desired to obtain by Letters Patent is:

1. In a dual rotation propeller comprising fore and aft axially spaced hub units adapted to be driven at equal and opposite speeds, blades carried by each of said hubs and mounted for pitch changing movements relative thereto, means for changing the pitch of said blades carried by each

of said hubs, and a fluid reservoir carried by said forward hub providing a scavenging chamber having an aft opening therein, gear means for coordinating the pitch changing movements of the blades of said hubs including a shroud spanning the space between said hubs and having elements of said gear means journaled therein whereby said shroud normally remains stationary relative to said hubs, means providing lubrication fluid for said gear means, and sealing means interposed between said shroud and hubs providing a substantially fluid tight container which forms an axial extension of and communicates with said chamber.

2. In a dual rotation aircraft propeller having fore and aft axially spaced units driven in opposite directions, blades carried by each of said units and mounted for pitch changing movements relative thereto, power actuated pitch changing means carried by one of said units responsive to the blade pitch changing movements of the other of said units including a gear train forming a continuous connection therebetween, a cage surrounding said train and spanning the space between said units and having elements of said gear train journaled therein whereby said cage normally remains stationary during propeller rotation, a power generator carried by said one unit and operative in response to rotation of said one unit for actuating said pitch changing means including a connection to said cage, and conductor means for transmitting electrical power between said units comprising contact elements carried by said cage and cooperating contact elements carried by said units whereby the relative rotational velocity between said elements is normally equal to the rotational velocity of one of said units.

3. In a dual rotation propeller according to claim 2 wherein said cage has fore and aft ends and seals are provided between said cage and units adjacent said ends.

4. In a dual rotation aircraft propeller having fore and aft axially spaced units driven in opposite directions, blades carried by each of said units and mounted for pitch changing movements relative thereto, pitch changing means carried by one of said units responsive to the blade pitch changing movements of the other of said units including a gear train forming a continuous connection therebetween, said gear train consisting of a plurality of externally toothed driven gear elements, a cage surrounding said train and spanning the space between said units including journals for said gear elements whereby said cage normally remains stationary during propeller rotation, said pitch changing means including fluid control mechanism therefor, pump means carried by said one unit for actuating said pitch changing means including operative connections to said fluid control mechanism, and gear means fixed to said cage and operatively connected to said pump means whereby said pump means is energized at the speed of said one unit with respect to said gear means.

5. In a dual rotation propeller having fore and aft axially spaced hubs adapted to be driven in opposite directions, blades carried by each of said hubs and mounted for pitch changing movements relative thereto, pitch changing means carried by one of said hubs operative in response to movement of the blades of said other hub including a first geared interconnection therebetween; and means operatively interconnecting the blades of said one hub with said other hub including a sec-

ond geared interconnection therebetween, each of said geared interconnections including planetary pinions respectively, a cage surrounding said trains, said cage including a journal for each of said planetary pinions respectively, and reversing gears journalled in said cage and engaging said planetary pinions.

6. In a dual rotation propeller having fore and aft axially spaced hubs adapted to be driven in opposite directions, blades carried by each of said hubs and mounted for pitch changing movements relative thereto, pitch changing means carried by one of said hubs operative in response to movement of the blades of said other hub including a first geared interconnection between said pitch changing means and the blades of said other hub, and means operatively interconnecting the blades of said one hub with said other hub including a second geared interconnection therebetween, a cage having pinion gears journalled therein and means operatively connecting said pinion gears to said geared interconnections for positioning said cage in space at a predetermined rotatable position with respect to the pitch position of the blades of said one hub.

7. In a dual rotation propeller having fore and aft axially spaced hubs adapted to be driven in opposite directions, blades carried by each of said hubs and mounted for pitch changing movements relative thereto, pitch changing means carried by one of said hubs operative in response to movement of the blades of said other hub including a first geared interconnection between said pitch changing means and the blades of said other hub, and means operatively interconnecting the blades of said one hub with said other hub including a second geared interconnection therebetween, a planetary cage, a first pair of pinion gears fixed relative to each other and journalled in said cage, said pair of gears forming a part of said first geared interconnection, and a second pair of pinion gears fixed relative to each other and journalled in said cage, said second pair of gears forming a part of said second geared interconnection.

8. In a dual rotation propeller having fore and aft axially spaced hubs adapted to be driven in opposite directions, blades carried by each of said hubs and mounted for pitch changing movements relative thereto, pitch changing means carried by one of said hubs operative in response to movement of the blades of said other hub including a first geared interconnection between said pitch changing means and the blades of said hub, and means operatively interconnect-

55

ing the blades of said one hub with said other hub including a second geared interconnection therebetween, a planetary cage, a first shaft journalled in said cage, two pinion gears fixed to said first shaft and forming a part of said first geared interconnection, a second shaft journalled in said cage, and two pinion gears fixed to said second shaft and forming a part of said second geared interconnection.

9. In a dual rotation aircraft propeller having fore and aft axially spaced units driven in opposite directions, blades carried by each of said units and mounted for pitch changing movements relative thereto, pitch changing means carried by one of said units responsive to the blade pitch changing movements of the other of said units including a planetary gear train forming a continuous connection between said pitch changing means and the blades of said other unit, said planetary gear train including a cage, planetary pinions journalled in said cage, and driving and driven gears operatively connected for rotation with said units whereby said cage normally remains stationary during rotation of said units, said cage surrounding said train and spanning the space between said units, a planetary gear train connection between said other unit and the blades of said one unit comprising planetary pinions journalled in said cage for moving said cage in response to the pitch changing movements of said one unit whereby said cage is moved to inactivate said pitch changing means, and sealing means between said cage and said units whereby the relative rotation between said sealing means and said units is normally equal to the rotational velocity of one of said units.
